UNITED STATES PATENT OFFICE.

CHARLES L. SMITH, OF BROOKLET, GEORGIA.

BLOW-OUT PATCH.

1,103,848.

Specification of Letters Patent. Patented July 14, 1914.

Application filed May 16, 1913. Serial No. 768,098.

To all whom it may concern:

Be it known that I, CHARLES L. SMITH, a citizen of the United States, residing at Brooklet, in the county of Bulloch and State of Georgia, have invented new and useful Improvements in Blow-Out Patches, of which the following is a specification.

The invention provides a novel form of shoe or patch to be used for repairing pneumatic tires when the same become punctured, whereby the machine may be maintained in service until permanent repairs may be made.

The invention consists of a shoe or patch adapted to be placed about the inner tube opposite the puncture, said patch being separable on a medial line and having novel fastening means for securing the edges after the patch has been placed about the inner tube and said patch having a flap to overlap the joint and prevent injury to the inner tube.

The invention consists of the novel features, details of construction and combination of parts, which hereinafter will be more particularly set forth, illustrated in the accompanying drawing, and pointed out in the appended claim.

Referring to the drawing, forming a part of the specification, Figure 1 is a top plan view of a blow-out patch or shoe for the inner tube of pneumatic tires embodying the invention. Fig. 2 is a view similar to Fig. 1 with the patch or shoe partly open. Fig. 3 is a transverse section on the line $\alpha-\alpha$ of Fig. 1.

Corresponding and like parts are referred to in the following description, and indicated in all the views of the drawing, by the same reference characters.

The blow-out patch or shoe is of tubular form when in operative position and is intended to receive the inner tube of a pneumatic tire.

The numeral 1 indicates the patch or shoe which may be of any length or diameter and is usually formed of a number of plies of canvas which are cemented together, the ends of the shoe being scarfed or feathered to obtain a close fit between the inner tube and casing. The shoe curves in its length, depending upon the diameter of the tire for which it is designed. To admit of placing the patch or shoe about the inner tube it is separable along a longitudinal line which corresponds with a medial line upon the in-

ner side. A flap 2 is provided along one edge of the patch or shoe bordering upon the opening, said flap being designed to overlap the joint and to underlap the edge portion of the shoe bordering upon the opposite side of the opening. A plurality of loops 3 are secured to opposite edge portions of the patch or shoe. The loops 3 may be of any material and suitable fastening means may be employed for attaching them to the patch or shoe. It is preferred to construct the loops of metal straps and to secure such loops to the shoe by means of rivets 4. The loops at one edge of the shoe are located opposite the spaces formed between the loops secured to the opposite edge of the shoe, so that when the shoe is closed about the inner tube the loops have an alternate arrangement with their closed ends in a straight line corresponding with the abutting edges of the parts of the shoe bordering upon the opening. A stout wire 5 serves as the fastening means for connecting the edges of the shoe when brought together, said wire passing through the closed ends of the loops, after the latter have been brought into registering position. When it is required to remove the shoe from an inner tube the wire 5 is withdrawn from the loops and the shoe being released may be opened, thereby admitting of the inner tube being removed therefrom. After the shoe has been placed about the inner tube and its edges brought together with the ends of the loops overlapping the wire 5 is slipped through the loops, thereby forming connecting means whereby the shoe is made secure. The flap 2 overlaps the joint and prevents injury to the inner tube. When the shoe is in position it comes between the inner tube and the casing, as will be readily understood.

It will now be understood that by independently fastening each of the metal loops entirely on the outside face of the flexible body of the patch, by means of an individual rivet located at a point remote from the edge of the body, both marginal edges of the body are left free and flexible to accommodate themselves to the tube and casing and that by reason of the disposition of said loops and their fastening rivets, the marginal edges of the patch are brought into and held in close proximity to each other throughout their length when the coupling wire is inserted through the closed ends of the overlapping loops.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claim appended hereto.

Having thus described the invention what is claimed as new, is:

A blow out patch for the inner tube of a pneumatic tire, said patch consisting of a tubular body flexible throughout and divided longitudinally of its inner wall, rows of metal loops attached to said body and arranged to alternate with and overlap each

other at their closed ends, all of said loops being positioned wholly on the outside face of the body and each loop being independently fastened to the body by a rivet located at such distance from the marginal edge as to leave the latter free and flexible, a coupling wire inserted through said overlapping loops, and a flap fastened to the inside face of one of said marginal edges and overlapping the other marginal edge of the inside face of the latter, the disposition of said loops and their fastening rivets being such that when said coupling wire is inserted through said loops, the marginal edges of the flexible body lie in close proximity to each other throughout their length.

In testimony whereof I affix my signature in presence of two witnesses.

CHAS. L. SMITH.
